UNITED STATES PATENT OFFICE.

CHARLES A. BENEDICT, OF BELLVALE, NEW YORK.

ELECTRIC SAFETY APPLIANCE.

1,125,936.

Specification of Letters Patent.

Patented Jan. 26, 1915.

Application filed January 25, 1913. Serial No. 744,115.

To all whom it may concern:

Be it known that I, CHARLES A. BENEDICT, a citizen of the United States, residing at Bellvale, in the county of Orange and State 5 of New York, have invented new and useful Improvements in Electric Safety Appliances, of which the following is a specification.

My present invention relates to electric 10 safety appliances particularly adapted for use with apparatus, such as telephones, arranged for low-tension currents, whereby they are prevented from injury by a current of dynamic electricity of abnormal strength, 15 or static electricity conducted by connections in operative relation to such apparatus.

The principal objects of my invention are 20 to provide an apparatus of the character described which will permit the static electricity to jump or bridge certain conductors remote from the apparatus protected, and to provide means whereby currents of abnormal strength are shunted from such apparatus, but the main conductors brought 25 into operative relation to the apparatus after the strength of the abnormal current subsides.

Other objects of my invention will appear 30 in the following detailed description, taken in connection with the accompanying drawings, forming a part of this specification, in which drawings:

Figure 1 is a plan view constructed according to my invention. Fig. 2 is a side 35 elevation of the same. Fig. 3 is an end elevation of the same.

In the drawings where similar characters refer to similar parts, A designates a suitable base of insulating material, carrying 40 main line conductors B and C, which in the example shown are in the form of binding posts. Gap providing means D is disposed intermediate conductors B and C for controlling static electricity. This means D 45 may include suitable standards 4 and 5 mounted upon base A and carrying coaxial conductors 6 and 7, respectively. In the example shown the conductors are in the form of set screws having threaded engagement 50 with the standards and adapted to be manipulated through heads 8 to adjust them for the provision of a gap 9 of the desired length. Conductor B is suitably connected with standard 4 by conductor 10, while conductor C is suitably connected with standard 5 through conductor 11, both conduc-

tors 10 and 11 being embedded in or carried by base A.

The conductors for the leads of the apparatus to be protected are designated by E 60 and F and in the example shown are also in the form of binding posts carried by base A. In operative relation to means D and conductors E and F, I provide mechanism G for control of currents of abnormal 65 strength. This mechanism G includes a circuit breaker 12 one point 13 of which is conductively connected with conductor E as through wire 14, while the other point 15, which, in the example shown, is in the form 70 of an armature, is conductively connected with a standard 16 as through a wire 17.

In order to conductively connect standard 16 with one of the main line conductors, the current must traverse a fine threadlike conductor 18 one end of which is adjustably connected to the standard as by set screw 19. This conductor 18 controls the position of an oscillatable lever 20, carried by framework 21 and operatively connected with 75 main conductor B as through wire 22, by having its other end rigidly connected with said lever remote from its pivot point. As disclosed in the drawings, lever 20 has trunnion-like extensions 23 one of which rests 35 in a step-bearing 24 and the other is carried by a set screw 25 passing through frame 21.

It is to be noted that conductor C is in 80 conducting communication with conductor F through wire 26 and that the circuit breaker 12 includes a set screw 27, carried by element 13, and normally contacting with point or armature 15. Thus, a current of 85 normal strength, is conducted successively through conductor B, standard 4, wire 22, step-bearing 24, lever 20, conductor 18, standard 16, wire 17, circuit breaker 12, and wire 14 to conductor E. From this latter conductor the current passes through the 90 apparatus protected to conductor F, through wire 26 and on through conductor C.

In operative relation to armature 15 is 95 disposed the core 28 of an electro-magnet 29 which also has a core extension 30 opposite from the extension of core 28. The 100 lever 20 carries a contact 31 and an armature 32, the latter of which is for coaction with core extension 30. For coaction with contact 31 is an adjustable contact 33 carried by standard 34, this contact 33 being 105 in conducting relation with the coil of electro-magnet 29 as through wire 35. The op-

posite end of the coil of this electro-magnet is in communication with conductor C as through wire 36 suitably contacting with wire 26.

5 Means 37 is provided to place conductor 18 under tension and actuate lever 20 so that contact 31 may engage contact 33 and armature 32 engage core extension 30. However, the conductor 18 is so adjusted by manipulation of set screw 19 as to normally draw lever 20 against action of means 37 so that these elements do not engage when the appliance is inactive, or when a current of normal strength is being conducted by 10 this thread-like conductor. The means 37 may include a standard 38 mounted upon base A, a set screw 39 adjustably carried by said standard, and a tension spring 40 operatively connecting the set screw and lever 20.

20 The operation of the appliance is as follows:—Should either conductor B or C carry static electricity, the same bridges or jumps from one of the conductors 6—7 to 25 the other, seeking the path of least resistance. Should a current of abnormal strength enter the appliance, when first passing through thread-like conductor, it will heat the same, causing it to elongate and permit contact 31 to engage contact 33. Immediately the current is shunted and passes through the electro-magnet drawing armature 15 toward core 28. This action breaks the circuit at device 12 and the current passes on through conductor C. It is 30 to be noted that while the electro-magnet is energized the armature 32 will be held in contact with core extension 30 holding contacts 31 and 33 in engagement. Inasmuch as the current is no longer conducted through element 18, the same cools and contracts to some extent. Any suitable means may be provided to compensate for this 35 contraction, such as constructing the lever 40 20 of yieldable material. As soon as the strength of the current subsides the tension of conductor 18 is such as to withdraw armature 32 from core extension 30 and the 45 circuit is broken between conductors 31 and 50 32. This action permits armature 15 to return to a normal position completing the circuit through conductor 18 and wires 14 and 17.

Changes in details may be made without departing from the spirit or scope of my invention; but,

I claim:—

1. In an electric safety appliance, the combination with two main conductors, of 55 a circuit breaker having two points normally in engagement; electro-magnetic means adapted to break the engagement of the points of said circuit breaker when energized; two contacts, one of which is in conducting communication with one of the

leads of the coil of said electro-magnetic means; a movable member carrying the other of said contacts; a conductor for communication with one of the main conductors, expansible to a material degree when carrying a current of abnormal strength, in conducting relation to one of the points of said circuit breaker and the said contact of said movable member, and operatively connected with the latter to permit the said contact carried thereby to engage its coacting contact only when said conductor is so expanded; means for connecting the other point of said circuit breaker with the apparatus to be protected; and, means for connecting the other lead of said electro-magnetic means with the other of the main conductors, substantially as and for the purpose set forth.

2. In an electric safety appliance, the combination with two main conductors, of a circuit breaker having two points normally in engagement, one of which points being constructed to serve as an armature; an electro-magnet having its core in operative relation to the said armature points of said circuit breaker; two contacts, one of which is in conducting communication with one of the leads of the coil of said electro-magnet; a movable member carrying the other of said contacts; a conductor for communication with one of the main conductors, expansible to a material degree when carrying a current of abnormal strength, in conducting relation to one of the points of said circuit breaker and the said contact of said movable member, and operatively connected with the latter to permit the said contact carried thereby to engage its coacting contact only when said conductor is so expanded; means for connecting the other point of said circuit breaker with the apparatus to be protected; and, means for connecting the other lead of said electro-magnet with the other of the main conductors, substantially as and for the purpose set forth.

3. In an electric safety appliance, the combination with two main conductors, of a circuit breaker having two points normally in engagement; electro-magnetic means adapted to break the engagement of the points of circuit breaker when energized; two contacts, one of which is in conducting communication with one of the leads of the coil of said electro-magnetic means; a movable member carrying the other of said contacts; a conductor for communication with one of the main conductors, expansible to a material degree when carrying a current of abnormal strength, in conducting relation to one of the points of said circuit breaker and the said contact of said movable member, and operatively connected with the latter to per-

mit the said contact carried thereby to engage its coacting contact only when said conductor is so expanded; means for connecting the other point of said circuit breaker with the apparatus to be protected; means for connecting the other lead of said electro-magnetic means with the other of the main conductors; and, means for retaining said movable member with the said two contacts engaging when said electro-magnet is energized by a current of abnormal strength, substantially as and for the purpose set forth.

4. In an electric safety appliance, the combination with two main conductors, of a circuit breaker having two points normally in engagement; electro-magnetic means adapted to break the engagement of the points of circuit breaker when energized; two contacts, one of which is in conducting communication with one of the leads of the coil of said electro-magnetic means; a movable member carrying the other of said contacts; a conductor for communication with one of the main conductors, expandible to a material degree when carrying a current of abnormal strength, in conducting relation to one of the points of said circuit breaker and the said contact of said movable member, and operatively connected with the latter to permit the said contact carried thereby to engage its coacting contact only when said conductor is so expanded; means for connecting the other point of said circuit breaker with the apparatus to be protected; means for connecting the other lead of said electro-magnetic means with the other of the main conductors; and, means for retaining said movable member with said two contacts engaging when a current of abnormal strength is being conducted thereby, substantially as and for the purpose set forth.

5. In an electric safety appliance, the combination with two main conductors, of a circuit breaker having two points normally in engagement; electro-magnetic means adapted to break the engagement of the said points of said circuit breaker when energized; two contacts, one of which is in conducting communication with one of the leads of the coil of said electro-magnetic means; a movable member carrying the other of said contacts; a conductor for communication with one of the main conductors, expandible to a material degree when carrying a current of abnormal strength, in conducting relation to one of the points of said circuit breaker and the said contact of said movable member, and operatively connected with the latter to permit the said contact carried thereby to engage its coacting contact only when said conductor is so expanded; means for connecting the other point of said circuit breaker with the apparatus to

be protected; means for connecting the other lead of said electro-magnetic means with the other of the main conductors; and, an armature operatively connected with said movable member for coaction with the core of said electro-magnet to retain the said two conductors in engagement when said electro-magnet is energized by a current of abnormal strength, substantially as and for the purpose set forth.

6. In an electric safety appliance, the combination with two main conductors, of a circuit breaker having two points normally in engagement; electro-magnetic means adapted to break the engagement of the said points of said circuit breaker when energized; two contacts, one of which is in conducting communication with one of the leads of the coil of said electro-magnetic means; a movable member carrying the other of said contacts; a conductor for communication with one of the main conductors, expandible to a material degree when carrying a current of abnormal strength, in conducting relation to one of the points of said circuit breaker and the said contact of said movable member, and operatively connected with the latter to permit the said contact carried thereby to engage its coacting contact only when said conductor is so expanded; means for connecting the other point of said circuit breaker with the apparatus to be protected; means for connecting the other lead of said electro-magnetic means with the other of the main conductors; and, an armature carried by said movable member for coaction with the core of said electro-magnet to retain the said two conductors in engagement when said electro-magnet is energized by a current of abnormal strength.

7. In an electric safety appliance, the combination of two main conductors, a circuit breaker having two points normally in engagement; electro-magnetic means adapted to break the engagement of said point of said circuit breaker when energized; two contacts, one of which is in conducting communication with one of the leads of the coil of said electro-magnetic means; an oscillatable lever carrying the other of said contacts; a thread-like conductor in conducting communication with one of said main conductors, expandible to a material degree when carrying a current of abnormal strength, said thread-like conductor having connection intermediate said lever and a stationary point and in conducting relation to one point of said circuit breaker, and being tensioned to permit movement of said lever for engagement of the said two contacts only when so expanded; means for connecting the other point of said circuit breaker with the apparatus to be protected; and, means for connecting the other lead of the coil of said electro-magnetic means with the

other of said main conductors, substantially as and for the purpose set forth.

8. In an electric safety appliance, the combination with two main conductors, of a circuit breaker having two points normally in engagement; electro-magnetic means adapted to break the circuit through said circuit breaker when energized; two contacts, one of which is in conducting communication with one of the leads of the coil of said electro-magnetic means; an oscillatable lever carrying the other of said contacts; a thread-like conductor for communication with one of said main conductors, expandable to a material degree when carrying a current of abnormal strength, said thread-like conductor having adjustable connections

intermediate said lever and a stationary point and in conducting relation to one point of said circuit breaker, and being tensioned to permit movement of said lever for engagement of the said two contacts only when so expanded; means for connecting the other point of said circuit breaker with the apparatus to be protected; and, means for connecting the other lead of said electro-magnetic means with the other of said main conductors, substantially as and for the purpose set forth. 20 25
